(57) **CLAIM**

The ornamental design for archery release, as shown and described.

DESCRIPTION

FIG. 1 is a perspective view of the archery release embodying the new design;

FIG. 2 is a top view thereof;

FIG. 3 is a left side view thereof;

FIG. 4 is a right side view thereof;

FIG. 5 is a front view thereof; and,

FIG. 6 is a rear view thereof.

FIGS. 1–6 show features of an archery release in phantom lines. These features are shown for environmental purposes and do not form any part of the claimed design. Further, the phantom lines immediately adjacent the solid-line portions of the design form the boundary of the design, with the phantom lines forming no part of the claimed design.

The design is shown broken apart along its length to indicate that no specific length is claimed.
